UNITED STATES PATENT OFFICE

151,125

DESIGN FOR A PERFUME BOTTLE

Eli Gordon and Henry Sanders,
Los Angeles, Calif.

Application June 29, 1946, Serial No. 131,171

Term of patent 7 years

(Cl. D58—9)

To all whom it may concern:

Be it known that we, Eli Gordon and Henry Sanders, citizens of the United States, residing at Los Angeles, in the county of Los Angeles and State of California, have invented a new, original, and ornamental Design for a Perfume Bottle, of which the following is a specification, reference being had to the accompanying drawing, forming part thereof.

In the drawing

Fig. 1 is a side elevational view of a perfume bottle, showing our new design;

Fig. 2 is a front elevation; and

Fig. 3 is a vertical section.

We claim:

The ornamental design for a perfume bottle, as shown.

ELI GORDON.
HENRY SANDERS.
